CLAIM

The ornamental design for packaging as shown and described.

DESCRIPTION

FIG. 1 is a bottom front isometric view of packaging showing the claimed design;

FIG. 2 is a top rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a bottom front isometric view thereof in an environment in which it may be used.
The broken lines in the figures show environment that forms no part of the claimed design.

1 Claim, 7 Drawing Sheets
